UNITED STATES PATENT OFFICE.

OSWALD S. PULLIAM, OF PITTSBURGH, PENNSYLVANIA, ASSIGNOR TO PITTSBURGH EQUIPMENT COMPANY, OF PITTSBURGH, PENNSYLVANIA, A CORPORATION OF PENNSYLVANIA.

END SILL FOR CARS.

1,044,818.

Specification of Letters Patent.

Patented Nov. 19, 1912.

Application filed April 7, 1908. Serial No. 425,585.

To all whom it may concern:

Be it known that I, OSWALD S. PULLIAM, of Pittsburgh, in the county of Allegheny and State of Pennsylvania, have invented 5 certain new and useful Improvements in End Sills for Cars, of which the following is a specification.

The object of my invention is to provide 10 a new and improved end-sill for railway cars.

In the accompanying drawing, which 15 illustrates applications of my invention, Figure 1 is a rear perspective view of an end-sill embodying my invention; Fig. 2 a front perspective view of the form of Fig. 1; Fig. 3 an elevational view of a modified form of end-sill; and Fig. 4 a part elevational and a part sectional view, the section being taken on line 4—4 of Fig. 1.

20 Referring to the drawing, the end-sill proper, as illustrated and as preferred, is made as an integral cast-metal structure and comprises a vertically extending member 1, a series of pockets 2 adapted to receive the 25 center-sill, the side-sills and the intermediate-sills of a car; a plurality of pockets 3 adapted to receive corner posts or upright members entering into the construction of a car-body.

30 In the drawing, I have shown only two pockets 3 designed for two corner-posts, but additional similar pockets may be provided for intermediate upright members. The vertically extending member 1 is formed 35 with protected openings 4, adapted to receive truss-rods, and with push-pockets 5. Extending inwardly from the vertical member and entering into the formation of the pockets for the longitudinal car-sills, I employ a floor supporting member 6. This member or ledge is designed to support the ends of the car flooring 7, as particularly shown by Fig. 4. Extending above the upper surface of the car-flooring and at right 45 angles with the member 7 I provide a member or portion 8. This portion 8 is designed to protect the lower ends of the boards entering into the construction of the ends of the car-body.

50 As shown by the several views of the

drawing, I deepen the end-sill at its central portion and provide means for supporting a draw-bar, not shown. In the form of Fig. 3 the vertical member is tapered and cut away to receive the draw-bar, while in the form of Fig. 1 the supporting plate 9 is formed to receive the draw-bar. In both forms the plates 9 and 9* are preferably made separate from the end-sill proper.

What I claim is:

1. The combination with a car-flooring, 60 of an integral cast metal end-sill comprising a vertical web and of channel form in cross section, a plurality of sill receiving members projecting from the rear face of the web, a floor supporting member entering into the formation of the sill receiving members, said car flooring disposed on the floor supporting member, and a vertical member projecting above the car-flooring and the web of the end-sill, said vertical member extending substantially the length of the end-sill and disposed at right angles to the floor supporting member.

2. The combination with a car-flooring, 75 of an integral cast metal end-sill comprising a vertical web and of channel form in cross section with the front face of the web formed with protected truss-rod openings, 80 a plurality of sill receiving members projecting from the rear face of the web, a floor supporting member entering into the formation of the sill receiving members, said car-flooring disposed on the floor supporting member, and a vertical member projecting above the car-flooring and the web of the end-sill, said vertical member extending substantially the length of the end-sill and disposed at right angles to the floor 85 supporting member.

3. The combination with a car-flooring, 90 of an integral cast metal end-sill comprising a vertical web and of channel form in cross section with the front face of the web formed with protected truss-rod openings 95 and push-pockets, a plurality of sill receiving members projecting from the rear face of the web, a floor supporting member entering into the formation of the sill receiving members, said car-flooring disposed on 100

the floor supporting member, and a vertical member projecting above the car-flooring and the web of the end-sill, said vertical member extending substantially the length of the end-sill and disposed at right angles to the floor supporting member.

In testimony whereof I affix my signature in presence of two witnesses.

OSWALD S. PULLIAM.

Witnesses:

A. C. WAY,

W. G. DOOLITTLE.
